UNITED STATES PATENT OFFICE.

THOMAS J. HARFORD, OF JERSEY CITY, NEW JERSEY, ASSIGNOR OF ONE-HALF TO J. J. BAMBERGER & CO., A CORPORATION OF NEW YORK.

ADJUSTABLE FRAME.

No. 898,047.

Specification of Letters Patent.

Patented Sept. 8, 1908.

Application filed August 26, 1907. Serial No. 390,219.

To all whom it may concern:

Be it known that I, THOMAS J. HARFORD, a citizen of the United States, residing at Jersey City, in the county of Hudson and 5 State of New Jersey, have invented certain new and useful Improvements in Adjustable Frames, of which the following is a specification.

This invention relates to adjustable frames, 10 and more particularly to frames adapted to support a lace panel.

The invention has for its object the production of a frame which is adjustable and is adapted to stretch lace curtains such as 15 are used extensively in hotel windows and vestibule doors of private houses.

A further object of the invention is to provide an adjustable frame which may be contracted or expanded both vertically and 20 transversely, and to construct the same in such a manner that the ends or edges of the curtain will be entirely concealed from view, thereby giving a neat and attractive appearance to the frame.

25 A still further object of the invention is to provide an adjustable frame of the character above described, and to construct the same in such a manner that the panel placed thereupon can be centered with geometrical accuracy as the adjustment makes it possible to get every line in the net perfectly straight.

While I have shown and described my adjustable frame as applied to window or door panels, I desire it to be distinctively 35 understood that it may be used by slight alterations which are entirely within the scope of my invention, for various other purposes, such as embroidery frames, screens, sieves, etc.

40 With these ends in view, the invention consists in certain component and coöperative parts, and in the novel manner of combination and arrangement of said parts, all of which will be hereinafter more fully described and specifically pointed out in the appended claims.

In the drawings forming a part of this specification: Figure 1, is a side elevation of a window frame, illustrating my improved 45 adjustable frame as applied, Fig. 2, is a sectional view, and Fig. 3, is a detailed view, illustrating the telescopic side sections.

Referring by numerals to the drawings, 1

represents a frame of the usual type such as are employed in windows. Secured upon 55 said frame in any desirable manner is my improved adjustable frame 2 consisting of four corresponding right angular pieces 3, which are formed with a flat base 4, and a curved face 5, which extends over the edge of the 60 base 4 and is provided with a series of teeth 6. One leg of the angular piece is somewhat 65 smaller than the other, and is provided with a locking means 7, adapted to engage a slot 8 in the larger leg in one of the corresponding angular pieces which telescopes the same.

It will be readily seen that when the four angular pieces are assembled that it produces a frame which may be adjusted either vertically or laterally and securely locked in any 70 desired position, and further that a frame or panel mounted thereupon by slipping the meshes approximately near the edge over the teeth may be stretched in any desired direction and the ends entirely hidden from 75 view by tucking the same between the base and curved face of the angular pieces.

I desire it to be understood that I do not 80 limit myself to the exact details of construction, as various minor changes may be resorted to without sacrificing any of the principles or advantages of this invention.

Having thus described the various features of my invention, what I claim as new and desire to secure by Letters Patent is:

1. In an adjustable frame, four corresponding angular sections, each section consisting of a base having a flange which is curved over said base and provided upon its edge with a series of teeth, of telescopic connections between the said sections, and means for locking the said telescopic connections together, substantially as specified. 90

2. In an adjustable frame, corresponding telescopic sections, each section being provided with a locking means, the said sections consisting of a flat base having a flange which is curved over the base and provided with a series of teeth adjacent to the free edge of the base and a channel or groove 95 formed by the said flange and base, substantially as shown and for the purpose specified.

THOMAS J. HARFORD.
